UNITED STATES PATENT OFFICE.

ELIZABETH GILMORE, OF GREENCASTLE, INDIANA.

CURTAIN-DRIER.

SPECIFICATION forming part of Letters Patent No. 461,608, dated October 20, 1891.

Application filed September 8, 1890. Serial No. 384,291. (No model.)

To all whom it may concern:

Be it known that I, ELIZABETH GILMORE, a citizen of the United States, residing at Green-
5 castle, in the county of Putnam and State of Indiana, have invented a new and useful Cur-
tain-Drier, of which the following is a speci-
fication.

This invention relates to a laundry, and more especially to the devices used therein for
10 holding lace curtains and other fine articles distended when they are drying; and the ob-
ject of the invention is to produce a device of this character capable of being stored away in a very small space.

15 To this end the invention consists, broadly speaking, of a frame whose side bars are composed of pieces hinged together, together with the specific details of construction of the parts of such frame, all as hereinafter more
20 fully described and claimed, and as illustrated in the drawings, in which—

Figure 1 is a plan view of a drying-frame embodying my improvements. Fig. 2 is a side elevation of one of the side bars of said frame when distended, and Fig. 3 the same when folded. Fig. 4 is a section through one side bar.

Referring to the said drawings, the frame consists of two side and two end bars held together at the points where they cross each other at the corners of the frame by strong clamps C in the ordinary well-known manner, and such points of connection can be adjusted to regulate the size of the frame to agree with 30 that of the curtain to be supported thereby, all as is well understood and forming no part of the present invention.

Each side bar of the frame consists of two inner pieces I and two outer pieces O, all provided with pins P in their upper faces, over which the curtain is to be hooked. The outer pieces are connected at their inner ends with the outer ends of the inner pieces by ordinary 35 hinges H, whose leaves are preferably secured to the lower faces of the two pieces, so that the outer pieces can be bent downwardly, but the striking of their ends against the ends of the inner pieces will prevent their bending upward. Secured to the inner and outer 45 edges of both inner pieces I are metallic arms A, whose inner ends are curved or bent, as at B, and are provided with registering per-

forations at their inner ends, which stand the same distance from the lower faces of the inner members as the thickness of the outer 55 ends of the outer members. Through each pair of registering perforations is passed a rivet R, pivotally connecting the pair of arms A at each edge of the inner pieces.

The side bars of the frame being distended, 60 as shown in Fig. 2, if they are supported at their ends—that is, at the corners of the frame—they cannot sag at their centers or between their ends, because the pivotal and hinged connections between the pieces of each 65 side bar are in the nature of knuckle-joints. The side bars are connected by the clamps C to make up a frame of the desired size. The curtain is supported upon this frame, and the corners of the frame are supported by any 70 suitable means. (Not shown.)

After the curtain has been dried and it is desired to store away the frame in the smallest possible space the clamps C are removed, the curtain disconnected from the pins P, and each member folded to the position shown in Fig. 3. In so folding a member the outer pieces O are first bent downwardly against the under sides of the inner pieces I, with their outer ends standing between the pairs 80 of arms A. The inner members I are then folded about the pivots R, so that the upper faces of the outer members O come in contact with each other, as shown in Fig. 3, and the side bar is reduced to one-quarter its length 85 when distended. As this length is about fourteen feet, more or less, the reduction there-
of to this extent is extremely useful, in that the device can then be stored away in a com-
paratively small space or in a short cupboard. 90

In order that the heads of the pins P will not come in contact with each other or with the upper faces of the outer pieces O when the side bars are folded, as in Fig. 3, I make the side bars of the cross-section, shown in 95 Fig. 4—that is, with their inner upper cor-
ners beveled or grooved, as shown at G—and the pins P are seated in the bevels of these cut-away corners so deeply that their heads will not project above the plane of the upper 100 face of the bar.

What I claim as new is—

The herein-described curtain-drier frame, the same comprising end bars and side bars

crossing at the corners of the frame, means for detachably and adjustably connecting them at such points, the end bars being of one section and the side bars of two, arms A, secured to the edges of meeting ends of the side sections and having downwardly-bent ends B pivotally connected at points remote from the lower faces of said sections by the thickness of the bars, each section comprising two members of equal length with their ends in contact and connected by a hinge H on their under faces, and each bar being cut away, as

at G, along its upper inner corner, and pins P, seated in said cut-away portions, with their outer ends below the planes of the upper faces of said pieces, all as and for the purpose set forth. 15

In testimony that I claim the foregoing as my own I have hereto affixed my signature in presence of two witnesses.

ELIZABETH GILMORE.
